United States Patent Office

Des. 197,743
Patented Mar. 17, 1964

197,743

PROJECTION CABINET

Guy Zwahlen and Horace W. Nickerson, Dade County, Fla., assignors to Zwahlen, Inc., Miami Beach, Fla., a corporation of Florida

Filed Feb. 13, 1963, Ser. No. 73,578

Term of patent 14 years

(Cl. D61—1)

FIG. 1.

FIG. 2.

FIG. 3.

FIG. 5.

FIG. 4.

FIG. 1 is a front perspective view of a projection cabinet showing our new design;

FIG. 2 is a rear perspective view thereof;

FIG. 3 is a front elevational view thereof;

FIG. 4 is a side elevational view thereof; and

FIG. 5 is a top plan view thereof.

The side opposite that shown in FIGS. 1, 2 and 4 is substantially plain and unornamented.

We claim:

The ornamental design for a projection cabinet, as shown and described.
